UNITED STATES PATENT OFFICE.

AUGUSTINE C. WEST, OF CAMBRIDGE, MASSACHUSETTS.

OIL-STOVE.

SPECIFICATION forming part of Letters Patent No. 530,609, dated December 11, 1894.

Application filed March 22, 1894. Serial No. 504,603. (No model.)

To all whom it may concern.

Be it known that I, AUGUSTINE C. WEST, a citizen of the United States, residing at Cambridge, in the county of Middlesex and State 5 of Massachusetts, have invented certain new and useful Improvements in Oil-Stoves; and I do hereby declare the following to be a full, clear, and exact description of the invention, such as will enable others skilled in the art to 10 which it appertains to make and use the same, reference being had to the accompanying drawings, and to figures of reference marked thereon, which form a part of this specification.

15 This invention relates to improvements in oil-stoves particularly that class in which a central draft heater is employed.

This invention may be considered as relating 20 to that class of heater shown and described in an application, Serial No. 437,336, filed in my name on July 20, 1892.

My improvements consist, first, in the peculiar arrangement of the chimney holder, whereby the heat, which is generated is prevented 25 from being imparted to the wick-tube either by conduction, convection or radiation; secondly, in the extension of the wick-tube cylinder through and below the base of the oil reservoir, further subdividing said cylinder 30 by an annular plate or partition and in perforating the wall of the cylinder both above and below said partition and thus provide for air currents; thirdly, in providing a jacket for the chimney of the heater in order that all heat 35 radiated from the chimney proper may be confined and conveyed into the hot air receptacle. In this way the effect of the heater is intensified.

Other features embodied in my invention 40 will be more fully hereinafter described.

The drawings represent in Figure 1, a side elevation partly in section of an oil-stove embodying my invention. Fig. 2 is a vertical diametrical section of the heater in part showing 45 the various component elements somewhat enlarged. Figs. 3 and 4 are perspective views of different forms of the cap or chimney holder. Figs. 5 and 6, are similar views of two forms of construction of the annular 50 plate which supports the chimney-holder.

In the drawings Fig. 1, shows an oil stove of the class before referred to, composed of a

rectangular structure or stove 2 open at the sides and preferably supported upon legs or posts 3, suitably braced by longitudinal tie rods 4. The base 5 of this structure or stove is formed of some light good non-conducting material as wood, which is to be covered with sheet metal 6 and beneath said base is hung the oil-reservoir 7. In this way the latter is 60 always kept cool and uninfluenced by the heaters 8. These latter may be varied in number according to the size and power of the stove. Preferably in general shape these heaters are sections of cylinders and are surrounded by the metallic stove-top or hot air chamber 9 which covers the stove and serves the usual function of being adapted to support cooking utensils. Furthermore the usual apertures 10 are also provided, when greater 70 heat is required in cooking. The lower portions of the heaters pass through the oil reservoir and extend through it and beyond.

The wick-tube 12 is a double cylinder, composed of inner and outer wall tubes 13, 14 respectively, while a perforated wick-raising tube 15, the perforations being shown by the broken black line in Fig. 2, is operated by a toothed wheel 16. Inclosing the wick-tube is the wick-tube cylinder 17 somewhat larger in 80 diameter to form an air channel or space for free passage of air. Said cylinder is divided into two portions 41, 42, respectively upper and lower by means of a removable annular plate or partition 43, shown in Fig. 2 as imperforate. This partition rests upon a bead or ledge 45, which contracts the bore of the wick-tube at this point. Circumferentially of the wick-tube at a point just below this plate 43, are created a number of apertures 90 46. Hence as air rises up through the lower chamber it is prevented from passing above the partition 43 and escapes outwardly through said apertures. Conversely to allow ingress of air into and through the upper 95 part of the wick-tube this element is pierced with numerous small holes 40. In the drawings this perforated portion is shown as a separate piece, but it may be formed integral with the wick-tube cylinder proper 17.

The wick-tube is supplied with oil from the oil-reservoir by means of short pipes 18, which extend across the lower wick-tube chamber 42.

Within the inner wall tube 13 of the wick-

tube 12 and supported thereby is placed a removable air deflector or flame spreader 20 composed of a foraminous cone 21, which is inclosed within and capped by an outwardly flaring or concave ring 23, likewise perforated and surmounted with a circular imperforate disk 24. Since the heat generated at this point is considerable, and to prevent disengagement of the cone 21 from the ring 23, the lower portion of the latter is equipped with a solid metallic band 47. The apex of the cone rests against the under surface of the plate 24, while the lower edge of the band is turned inwardly to form a lip or flange 48. Thus the cone is kept firmly in place and no solder is required. The composition of this band may be of brass or other metal not easily affected by a high degree of heat.

The several parts above described are to prevent the too sudden passage of air through the central bore of the wick-tube, and the perforations tend to break up and retard the air currents, which finally are allowed to reach the flame under such conditions that a proper air supply is furnished and still no smoking or flickering of the flame occurs.

One of the features of this invention is embodied in the construction and method of mounting the chimney-holder, whereby the latter is made readily removable in order to light the heater, and moreover the conduction and radiation of heat is prevented in a great measure. In this way the lower portion of the heater is kept cool. In the present instance the chimney holder or cap is shown at 25, as a circular disk formed with a circular aperture 26, and with two outwardly extending horizontal ledges 27, 28. This chimney holder is supported upon the foraminated annular plate 29, which surmounts the wick-tube cylinder before mentioned. As before alluded to, and as shown in the drawings this perforated portion is made as a separate sleeve piece 50, preferably adapted to fit about and engage the upper extremity of the wick-tube cylinder, and is surmounted by the annular perforated plate 29. Fig. 6, represents the plate 29 as separate from the sleeve 50, while Fig. 5 is an illustration of the same in which the plate and sleeve are made integral. This latter construction simplifies the cost.

Since the chimney-holder rests upon and is supported by the plate 29 my object is to prevent the least metallic contact possible between said parts, in order to overcome the conduction of heat, which would otherwise occur. To this end, as shown, in Figs. 3 and 5, the plate 29 is made flat, while the chimney-holder is fitted with a series of projections or bosses 30, whereby free air circulation is provided to keep the parts cool, and at the same time supply a current of air, which flows above the plate 29 and externally about the frame; this air current passing through the central orifice of the holder. It is evident that since the annular plate 29 has a current of air passing above it, and a second flowing

directly through it, there is little or no tendency to heat, and the temperature of the parts on which it rests are never high even when the stove is in use. An alternative construction of the plate is shown in Fig. 6, where the plate has a series of radial ribs 31, while those on the holder are omitted. In either case the least metallic contact is presented, and as the external air supply is continually passing between the annular plate 29 and the chimney-holder 25 little or no heat is transmitted to the wick-tube or to the wick-tube cylinder.

Another important feature in this stove consists in providing the chimney 32 with a jacket 34. These parts, the chimney and jacket are supported respectively upon the ledges 27, 28 before mentioned. Hitherto in apparatus of this class, the hot air radiating from the chimney has been lost to a great extent, generally escaping into the room, and only such air as passes upward directly through the chimney itself has been utilized. In my invention I inclose the chimney within the jacket and extend the latter into the hot air chamber 9. Thus all the heat radiating from the chimney proper is confined and serves to heat a column of air, which enters through the orifice 35 at the base, and is passed into the hot air chamber to intensify the temperature at that point. A transparent medium 36 in the jacket in conjunction with that in the chimney permits the height of the flame to be determined at a glance.

What I claim is—

1. In a central draft-heater, the combination with an oil-reservoir, and a wick-tube cylinder which extends through the reservoir, of a wick-tube within the wick-tube cylinder, but non-contiguous thereto, and a transverse partition, said partition to extend across the space between the wick-tube cylinder and the wick-tube, substantially as stated.

2. In a central draft burner, the combination with an oil-reservoir, and a wick-tube fed from said reservoir, of a wick-tube cylinder extending up through the reservoir, said cylinder foraminated at the upper portion and open at the bottom and surrounding the wick-tube, and a removable imperforate annular partition transversely across the space between the wick-tube cylinder and the wick-tube, substantially as and for the purposes explained.

3. In a central draft-heater, a wick-tube, the central flame spreader, and a wick-tube cylinder which incloses said wick-tube, and a removable imperforate annular partition which divides the space between the wick-tube and wick-tube cylinder into an upper and lower portion, combined with an annular perforated plate 29, and a detachable chimney-holder supported upon said plate, one of said parts provided with ribs or bosses substantially as described.

4. In central draft-heaters, an oil reservoir, a wick tube cylinder, combined with a remov-

able chimney-holder, a chimney, its inclosing jacket, and a hot air receptacle interconnected with the chimney and the jacket, substantially as stated.

5 5. In combination with an apertured hot air receptacle, and an oil-reservoir suitably mounted, a central draft heater supported between them and composed as follows:—a wick-tube cylinder perforated at the top portion and adapted to extend through the oil reservoir, the foraminous plate 29, a removable chimney holder, the chimney and its jacket, a central wick-tube adapted to project through the bottom of the wick-tube cylinder, the flame deflector, and means for allowing oil to pass from the oil reservoir across the wick-tube cylinder to the wick-tube, substantially as explained.

6 6. In a central draft heater, the combination with a wick-tube, its flame deflector, the inclosing wick-tube cylinder perforated in the upper portion, and the annular foraminated plate 29 which surmounts the same, of a removable chimney holder formed with outwardly extending horizontal ledges, and a series of inwardly projecting bosses adapted to contact with the said plate 29, substantially as set forth and stated.

7 7. In a central draft heater, the combination with a wick tube, its flame deflector, the inclosing wick-tube cylinder open at its lower end, and a transverse annular imperforate partition between the wick-tube and the wick-tube cylinder, of a foraminated sleeve 50 adapted to engage the top of said wick-tube cylinder, the annular foraminated plate 29 affixed to said sleeve, and a removable chimney holder fitted with outwardly extending ledges, and with a series of inwardly project-

ing bosses adapted to contact with said plate 40 29, substantially for purposes explained.

8. A detachable chimney-holder composed of an annular conical shaped ring having a central upper aperture to contain a flame spreader and wick, and formed with outwardly 45 extending ledges at or near its base and with a series of inwardly projecting bosses as supports for said holder, substantially as specified.

9. In a central draft-heater the combination with a wick-tube, its flame deflector, and a wick-tube cylinder, open at the lower end and inclosing but non-contiguous to said wick-tube, of an annular partition transversely in the space between said wick-tube and wick-tube cylinder, circumferential openings in 55 the wick-tube cylinder below the partition, and circumferential perforations in the said cylinder above the partition, substantially as set forth.

10. In a central draft-heater, a wick-tube, the flame deflector, and a wick-tube cylinder open at the bottom to create an air passage between the wick-tube and wick-tube cylinder, an imperforate annular partition 65 transversely across said air passage, openings in said cylinder above the partition for admission of air, perforations in said cylinder below said partition for escape of air, and a foraminous plate which caps the wick-tube cylinder, substantially as stated.

In testimony whereof I affix my signature in presence of two witnesses.

AUGUSTINE C. WEST.
